UNITED STATES PATENT OFFICE.

JOHN ANDERSON DAVISON, OF FRANKLIN, TERRITORY OF ALASKA.

BULLET.

1,252,325.

Specification of Letters Patent.

Patented Jan. 1, 1918.

Application filed September 22, 1914. Serial No. 863,051.

To all whom it may concern:

Be it known that I, JOHN A. DAVISON, of Franklin, in the Territory of Alaska, have invented certain new and useful Improvements in Bullets; and I do hereby declare the following to be a full, clear, and exact description of the invention, such as will enable others skilled in the art to which it appertains to make and use the same.

- 10 The object of this invention is to provide a bullet for small arms which will mushroom or expand at a point rearward of its front end, and preferably at or about its center, on impact with the body of an animal, a human body or any hard substance, and at the same time avoid the objection which exists as to mushrooming bullets heretofore known, namely, the insufficiency of the velocity to cause them to expand or mushroom.
- 20 In the accompanying drawings, Figure 1 is a longitudinal section of the preferred form of my invention, the mushrooming effect being produced by the expansion of a 15 portion of the two parts of the bullet. Fig. 2 is similar to Fig. 1 with the cylindrical plug omitted. Fig. 3 corresponds to Fig. 1, differing therefrom in that the nose of the bullet is rounded.
- 30 My present invention is capable of embodiment in various forms, and hence I do not restrict myself to any particular construction, the fundamental idea being that 25 on impact the point or forward portion of the bullet will remain intact, free to plow its way through the object struck and thus bore a hole for the passage of the expanded or deformed portion. Upon the point or forward portion of the bullet receiving sudden
- 40 check, upon impact, the resistance of a relatively weakened portion to the rear will be overcome by the inertia of the rearward part of the bullet, causing mushrooming to occur at a point intermediate the two parts of the bullet.

According to the form of my invention shown in Fig. 1 the front part 1 and the rear part 2 have each a centrally arranged cavity extending longitudinally thereof for some distance, and in such cavities I have shown a relatively easily expandable cylindrical

55 plug 3 which may be of any suitable metal, such as copper or amalgam, or of any vegetable substance such as hardwood. In Figs. 1 and 2 I have shown the bullet as having a pointed nose of the Spitzer type and as surrounded by a jacket 4. This jacket may be wholly omitted or caused to only partially incase the bullet. In Fig. 2 I have omitted the cylindrical plug and depend upon the 60 upsetting of the hollow cylindrical portions of the parts 1^a and 2^a to produce the mushrooming. The form shown in Fig. 3 corresponds to that indicated in Fig. 1 but differs therefrom in that the end of the forward 65 part 1^b is rounded at its point and the inclosing casing does not extend over the point. Of course, if desired this point may be flattened, and the casing likewise may extend over and completely cover or envelop the 70 rounded or flattened point.

By my invention I aim to maintain the proper balance of the bullet so as to insure its true and steady flight. While I prefer to make the two end parts of the bullet of 75 pure lead, lead and amalgam or any other suitable metal may be employed. When the intermediate cylindrical plug is used it is preferably made of copper or other soft metal, or vegetable matter. Although, as I 80 have before pointed out, this cylindrical plug may be omitted, provided the bullet is formed with a lessened resistance between its two parts, by the use of the cylindrical plug I obtain additional support for the 85 parts of the bullet and thus prevent any likelihood of the bullet being deformed during its passage or transit through the rifling of the barrel.

I claim as my invention:

1. A bullet composed of a forward part and a rearward part in end to end disposition, and a casing inclosing said parts, each of the latter having at its axial center a cavity extending from one end longitudinally 95 thereof, the opposed open ends of the two parts being at or about the center of the bullet.

2. A bullet composed of a forward part and a rearward part in end to end disposition, and a casing inclosing said parts, each of said parts having at its axial center a cav-

ity extending from one end longitudinally thereof, the opposed open ends of the two parts being at or about the center of the bullet, and a filler within the cavities of the two parts.

In testimony whereof, I have signed this

specification in the presence of two subscribing witnesses.

JOHN ANDERSON DAVISON.

Witnesses:

WILLIAM W. CURLEY,

HARRY B. ALLDIS.

It is hereby certified that in Letters Patent No. 1,252,325, granted January 1, 1918, upon the application of John Anderson Davison, of Franklin, Territory of Alaska, for an improvement in "Bullets," errors appear in the drawings requiring correction as follows: In Fig. 1, for the reference-numerals "1^b, 2^b, 6^b," read 1, 2, 3; Fig. 2, for the reference-numerals "1^c, 2^c," read 1^a, 2^a"; Fig. 3, for the reference-numeral "1^f" read 1^b; and that the said Letters Patent should be read with these corrections therein that the same may conform to the record of the case in the Patent Office.

Signed and sealed this 26th day of February, A. D., 1918.

[SEAL.]

F. W. H. CLAY,

Acting Commissioner of Patents.
